FIG. 1

FIG. 2

FIG. 3

FIG
4FIG. 5

The dominant features of my design are shown in solid lines, the broken lines indicating conventional ring binder spines.

I claim:

The ornamental design for a desk tray or the like, as shown and described.
